UNITED STATES PATENT OFFICE.

GEORGE LINDE, OF NEWARK, NEW JERSEY.

DESIGN FOR A FINGER-RING.

SPECIFICATION forming part of Design No. 21,371, dated March 8, 1892.

Application filed January 27, 1892. Serial No. 419,472. Term of patent 3½ years.

To all whom it may concern:

Be it known that I, GEORGE LINDE, a citizen of the United States, residing at Newark, in the county of Essex and State of New Jersey, have invented and produced a new and original Design for a Finger-Ring, of which the following is a specification, reference being had to the accompanying drawings, forming a part thereof, in which—

10 Figure 1 is a side elevation of a finger-ring, showing my design. Fig. 2 is a perspective view from above; and Fig. 3 is a perspective inside view of the ring, these three figures being deemed necessary to fully illustrate my 15 design.

Similar figures of reference indicate corresponding parts in all the views.

The leading feature of my design is the cruciform figures produced in relief upon the 20 table of the ring, the crown-like figure pro-

duced within the circle formed by the cruciform figures, and the panel 14, produced on the inside of the table. The ring 10 has on one side a table 11, which when viewed in elevation has a flat top surface, and produced 25 circumferentially and in relief upon the table are the cruciform figures 12, and near the center of the table and within the concentric line formed by the cruciform figures is a crown-like figure 13, and within the ring and 30 on the inside of the table is an ovoidal panel 14 for the reception of any suitable words or characters.

I claim—
The design for a finger-ring, herein shown 35 and described.

GEORGE LINDE.
